UNITED STATES PATENT OFFICE.

FRED B. COREY, OF SCHENECTADY, NEW YORK, ASSIGNOR TO GENERAL ELECTRIC COMPANY, A CORPORATION OF NEW YORK.

ELECTROMAGNET.

No. 811,277.

Specification of Letters Patent.

Patented Jan. 30, 1906.

Application filed July 15, 1904. Serial No. 216,644.

To all whom it may concern:

Be it known that I, FRED B. COREY, a citizen of the United States, residing at Schenectady, county of Schenectady, State of New York, have invented certain new and useful Improvements in Electromagnets, of which the following is a specification.

My invention relates to electromagnets, and is particularly applicable to electromagnets and solenoids for controlling semaphore-signals in railway systems, although it is not limited to this specific application, but may be used with advantage wherever it is desired to operate two devices selectively with a single magnet.

The object of my invention is to so arrange the connections between an operating-magnet and two or more devices to be moved—such, for instance, as semaphore-signals—that either or both of the devices may be moved selectively by the magnet and that the selective action may be controllable from a distance. I accomplish this by providing two dogs arranged to be actuated by the magnet and adapted to engage the two semaphore-signals, but normally held out of engagement with the semaphore-signals by a spring or similar device. I also provide a small selector-magnet for each dog which when energized moves the dog into engagement with the signal or other device to be moved. In this manner the actuating-magnet may be operatively connected to either or to both of the signals.

Another feature of my invention consists in the arrangement and connection of the selector-magnets so as to enable both selector and actuating magnets to be operated with great economy of current. In block-signal systems it is customary to arrange the signals to be held at "safety" by an electromagnet and to allow the signal to go to "danger" by gravity when the magnet is deenergized. This arrangement insures safety in operation, since the disabling of the electric circuits can produce no more serious effects than allowing the signals to go to "danger," and thereby delay traffic; but since the magnets must normally be energized in order to hold their signals at "safety" a large amount of current is constantly required. In Patent No. 765,550, issued to W. W. Brown July 19, 1904,

is disclosed a novel form of electromagnet so arranged that a maximum current is required only while the signal is being drawn to 55 "safety," while a much smaller current suffices to hold the signal in safety position. One feature of my invention consists in so arranging the selector-magnets that they may be used in connection with such an actuating-magnet and have the current reduced in their windings when the signal is set without letting the signal fall.

My invention will best be understood by reference to the accompanying drawings, in 65 which—

Figure 1 shows connections arranged in accordance with my invention between the operating-magnet and two signal-rods. Fig. 2 shows a plan view of a portion of said connections, and Fig. 3 shows diagrammatically the arrangement and connections of the circuits of the magnet-windings.

In Fig. 1 I have shown an operating-magnet of the type disclosed in the above-mentioned patent, No. 765,550. This magnet consists of an actuating-coil A, which when energized draws up the movable core B into the position shown in the drawings. Core B has at its lower end a slot b, which is loosely 80 yet positively engaged by a pin c, carried by the lever C, which is pivoted at c'. D is a dash-pot adapted to retard the upward movement of lever C under the influence of core B. The movable member, which is shown as the 85 outside member, attached to lever C, carries a lug d, which encircles an upright shaft E. The shaft E carries washers e and e', adapted to be engaged respectively by lug d upon the upward-and-downward movement of the 90 movable member of dash-pot D. F is a bridging member of conducting material, such as a metal disk, and is carried at the upper end of vertical rod E. Bridging member F when rod E is allowed to fall engages 95 the contacts f f'. f' is a spring which bears against the tapered insulating-block f", carried by shaft E, and which holds shaft E in any given position. G is a dog or catch pivoted at g on lever C and adapted to engage 100 the pin g' when lever C is in its raised position, as shown in Fig. 1. g' is a spring acting to hold dog G in engagement with the pin g'. As long as dog G is in engagement with

pin g' it serves to support the weight of lever C and the signal mechanism connected thereto, as well as the movable member of dash-pot D, and thereby relieves core B of any 5 downward strain thereon.

The operation of the mechanism as thus far described is as follows: If the core B and lever C are at their lowest positions and coil A is energized, core B will be drawn up, moving lever C and dash-pot D upward until the lug d , carried by the dash-pot D, engages the collar e and raises the bridging member F out of engagement with the contacts ff . When this occurs, a resistance is thrown into series 10 with the actuating-coil A, as will be herein-after explained, and the current-flow through actuating-coil A is reduced to an amount insufficient to hold up the weight of lever C and attached mechanism. Lever C and dash-pot 15 D accordingly drop back a small amount, sufficient to bring dog G into engagement with the pin g' , as shown in Fig. 1. Pin g' then takes the weight of lever C and the mechanism connected thereto, while the current flowing through coil A is still sufficient to hold up the weight of core B alone. Core 20 B and lever C are consequently maintained in the position shown in Fig. 1, and spring f' holds bridging member F raised out of engagement with contacts ff . This condition of affairs continues as long as coil A remains energized. When the circuit of coil A is opened, core B falls freely until the upper 25 end of slot b engages pin e and in falling strikes the toe g^2 of dog G, rotating it on its pivot against the pressure of spring g^2 and releasing it from engagement with pin g' . Lever C consequently falls, allowing the signal to go to "danger." Just before reaching its 30 lowest position lug d , carried by dash-pot D, engages the washer of collar e' on shaft E and pulls down bridging member F into engagement with contacts ff . The resistance is then cut out of the circuit of coil A, as will be 35 herein-after explained, and the coil is ready to receive its maximum current, when the circuit of the coil is again closed.

The arrangement as thus far described is fully disclosed in Patent No. 765,550, above 40 referred to, and has been described here merely for the purpose of enabling a clear understanding of my invention to be obtained.

The outer end of the lever C carries two pivoted dogs H and H'. One end of dog H carries a core, such as h , adapted to be pulled downward by a selector-coil I, and the other end is adapted to engage a notch j in the operating-rod J of a signal or other device to be 45 moved. The dog H is normally held out of engagement with rod J by a tension-spring K; but when coil I is energized the dog is rocked on its pivot against the tension of spring K, so as to bring its lower end into engagement 50 with rod J. The dog H' is similarly provided

with a core h' , a selector-magnet I', and a rod J'. This is clearly shown in Fig. 2. The circuits of the selector-coils I and I' are controlled by the relays L and L', respectively. Each selector-magnet consists of two portions or sections, one of which consists of a few turns of large wire, while the other section consists of a comparatively large number of turns of fine wire. This is indicated in Fig. 1. 70

Referring now to Fig. 3, the connections and operation of the selector-magnets will be explained. The relays L L' are shown connected, through switches S and S', to any suitable source of current. These relays may be controlled manually from a signal-house or may be connected in a track-circuit so as to operate like the relays in an ordinary automatic block-signal system. M represents a source of current for the operating-coil A controlling the two signals N and N'. 75 The coarse-wire sections of the selector-magnets I and I' have one terminal connected to the relays L and L' and the other terminals connected to contacts f . The fine-wire sections are similarly connected to the relays, 80 but have their other terminals connected to the resistance O, which is thrown into series with coil A when the bridging member F is raised in the manner that has been heretofore explained. The other terminal of coil A is 85 shown grounded by connection to one of the track-rails R. With both relays L and L' open the circuit of both the selector-magnets I and I' and of the actuating-coil A are 90 open. The core of coil A is consequently at its lowest position and bridging member F is 95 in engagement with the contacts f . Now if relay L is energized, as indicated in the drawings, a circuit is closed from the line M through the armature of relay L, through the coarse-wire section of selector-magnet I, 100 through bridging member F, and through actuating-coil A to earth. The dog H (shown in Fig. 1) is consequently brought into engagement with the operating-rod J of the 105 signal N, and coil A draws up its core, moving signal N to safety position. When this position is reached, bridging member F is lifted 110 out of engagement with contact f , as has been already described, and the connection between the coarse-wire section of coil I and actuating-coil A is broken. The circuit now 115 passes from the armature of relay L through the fine-wire section of relay I, through resistance O, and through actuating-coil A. 120 The current in both the actuating-coil and the selective device is consequently reduced, so that the greatest economy of current is obtained, while the number of effective turns of the selector-magnet is increased, so that it 125 does not release the signal. Obviously if both relays L and L' had been energized both the signals would have been moved to safety position, or if relay L' only had been energized signal N' would have been moved to 130

safety position and signal N left at "danger." Thus the selective control of both signals by a single actuating-coil is obtained.

In order to present a complete description 5 of my invention, I have illustrated and described a number of parts which are not essential to my invention. Consequently I do not desire to limit myself to the particular construction and arrangement of parts 10 shown, but I aim in the appended claims to cover all such modifications which are within the scope of my invention.

What I claim as new, and desire to secure by Letters Patent of the United States, is—

1. In combination with a plurality of devices to be moved, an actuating-magnet, a lever controlled by said magnet, a plurality of dogs carried by said lever, and selective means for moving said dogs into engagement 20 with said devices.

2. In combination with a plurality of devices to be moved, an actuating-magnet therefor, a lever controlled by said magnet, a plurality of selector-magnets carried by said 25 lever, and means controlled by said magnets for connecting said lever selectively to said devices.

3. In combination with a plurality of devices to be moved, a magnet-winding, a lever 30 arranged to be actuated thereby, a plurality of dogs carried by said lever and adapted to engage said devices, means for holding said dogs normally out of engagement with said devices, and selector-magnets adapted and arranged to move said dogs selectively into engagement with said devices.

4. In combination with a plurality of signals, notched operating-rods therefor, a single actuating-magnet for said rods, a plurality 40 of dogs arranged to be moved by said magnet and adapted to engage the notches on said rods, means for holding said dogs normally out of engagement with said notches, and selector-magnets adapted and arranged 45 to move said dogs selectively into engagement with said notches.

5. In combination with a plurality of devices to be raised, a single actuating-magnet therefor, selector-magnets controlling the 50 connections between said devices and said actuating-magnet and each comprising a coarse section and a fine-wire section of a greater number of turns, means for connecting the coarse-wire section only in circuit for raising, 55 and means for connecting the fine-wire sec-

tion in circuit when the device or devices are raised.

6. In combination with a plurality of devices to be raised, a single actuating-magnet therefor, selector-magnets controlling the 60 connections between said devices and said actuating-magnet, means for reducing the current-flow in said magnets when the device or devices are raised, and means for increasing the number of effective turns of the selector-magnets.

7. In combination with a plurality of devices to be raised, a single actuating-magnet therefor, selector-magnets controlling the 70 connections between said devices and said actuating-magnet, means for connecting said magnets selectively in series with the actuating-magnet for raising a device or devices, and means for decreasing the current-flow in the magnet-circuit and increasing the effective 75 turns in the selector magnet or magnets when said device or devices are raised.

8. In combination with a plurality of devices to be raised, a single actuating-magnet therefor, selector-magnets controlling the 80 connections between the several devices and the actuating-magnet, each of said selector-magnets comprising a coarse-wire section and a fine-wire section of greater number of turns, means for connecting the coarse-wire 85 sections of said magnets selectively in series with said actuating-magnet for raising a device or devices, and means for inserting a resistance in the magnet-circuit and including 90 said fine-wire sections in circuit when said device or devices are raised.

9. In a railway signal system, a plurality of semaphore-signals, a single actuating-magnet adapted to move said signals to safety, selector-magnets controlling the 95 connections between the several signals and said actuating-magnet, relays arranged to connect said selector-magnets selectively in series with the actuating-magnet for moving a signal or signals to safety, and means for 100 decreasing the current-flow in the magnet-circuit and increasing the effective number of turns in the selector magnet or magnets when said signal or signals are at safety.

In witness whereof I have hereunto set my hand this 13th day of July, 1904.

FRED B. COREY.
